DRAFT RIGGING

Filed Nov. 30, 1925

UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

DRAFT RIGGING

Application filed November 30, 1925. Serial No. 72,303.

This invention relates to draft rigging and, more particularly, to the connection between the coupler and yoke allowing for swivelling motion therebetween.

The principal object of the invention, generally considered, is the provision of an improved pivotal connection between the swivel portion of a swivel butt coupler and the main portion thereof as well as the provision of an improved retaining means for said pivotal means.

An object of the invention is to provide a pivotal connection between the yoke and coupler members of railway draft rigging in which the pivotal means, instead of being circular in cross section, is elongated longitudinally or formed oblong in cross section, preferably being rounded at the ends and flattened at the sides thereof for securing greater effectiveness in the connection between the coupler and yoke.

Another object of my invention is the provision of a swivel butt coupler formed with a swivel block pivotally connected with the butt portion of the coupler by means of an upright pin, said pivot pin being formed with its top portion flush with the top of the coupler and with its lower portion extending below said coupler proper and provided with retaining means for said pin whereby said coupler butt and swivel block are adapted for snugly fitting between the forwardly extending arms of a cooperating yoke, the portions of the yoke adjacent the lower end of the pin being downwardly offset for receiving the same.

A further object of my invention is the provision of a swivel butt coupler and its connection with an associated yoke of the vertical type, wherein the parts of the coupler butt are pivotally connected by means of a pivot pin preferably flattened along the sides thereof, said pin being retained in place by a shouldered portion thereon engaged by a flange or extension from the adjacent portion of the coupler for preventing downward movement thereof.

A still further object of my invention is the provision of a coupler, to the butt portion of which is pivoted a swivel block member,

the pivotal means therebetween being slotted for the reception of a key for connecting said coupler to a cooperating yoke and the pivotal means being retained in place by the lower end thereof being shaped for engaging a retaining portion on the coupler or a cotter for connecting the same thereto.

Other objects and advantages of my invention, relating to the particular arrangement and construction of the various parts will become apparent as the description proceeds.

In the drawings illustrating my invention, the scope whereof is defined by the appended claims:

Figure 1 is a plan view, partly in section, illustrating a coupler and associated yoke embodying the features of my invention.

Figure 2 is a longitudinal vertical substantially central view of the construction illustrated in Figure 1.

Figure 3 is a vertical sectional view of the yoke on the line 3—3 of Figure 2.

Figure 4 is a fragmentary sectional view illustrating an alternative retaining means for the pivot pin.

Figure 5 is a fragmentary detail sectional view illustrating a modified form of pivot pin retaining means.

Referring to the drawings in detail, like parts being designated by like reference characters, and first considering the construction illustrated in Figures 1 to 3, inclusive, there is illustrated a swivel butt coupler 1 connected to a yoke 2 which, in the embodiment illustrated, is of the vertical type, by means of a substantially horizontal draft key 3. Said key 3 serves to hold the coupler and yoke in alinement as well as connect the same and is supported, in the usual manner, between cooperating draft or center sills (not shown).

The swivel butt coupler 1 preferably comprises a butt or main coupler portion 4 and an auxiliary or swivel block portion 5 pivotally connected thereto by means of an upright pin 6, so that the parts move longitudinally as a unit on buff and draft swivel block portion 5, however, may, if desired, be considered as part of the yoke and is adapted to serve as the front follower thereof being

formed for engagement with cushioning mechanism, illustrated diagrammatically by dot and dash lines in Figure 2. The swivel block 5, in the present embodiment, is operatively connected to the yoke 2 for the transmission of draft forces therebetween by the key 3. For convenience I will designate the auxiliary member 5 as a swivel block, because it is swivelled with respect to the main coupler portion 4 and it may be considered as forming a two-part or articulated coupler stem. If desired, however, the swivel block may be considered as a front follower member of the yoke as it is connected thereto by means of the key 3 and suitable for engagement with associated cushioning mechanism.

The yoke, in the present instance, is shown as of the vertical type with upper and lower forwardly extending arms 7 and 8, respectively. Said arms are preferably connected by integral web or wall portions 9 and 10 extending on either side of the coupler butt and forming a hooded front end for said yoke. The key member 3 preferably passes through slots 11 and 12 in the wall portions of said yoke. The slots 11 and 12 are formed of such a size that the key 3 contacts therewith for the transmission of draft forces between the coupler and yoke but they allow the key to move rearwardly upon the application of buffing forces so that said forces are transmitted from the rear face of the swivel block directly to the cushioning mechanism before mentioned.

In the present embodiment, the coupler 1, and more especially the butt portion 4 thereof, is provided with rearwardly extending substantially or normally horizontal web or flange portions 13 and 14, said portions being curved along the rear faces or edges thereof coaxially with respect to the pivot pin 6. The swivel block 5 likewise is provided with forwardly extending normally horizontal web or flange portions 15, 16 and 17 which overlap, closely interengage or are intercalated with respect to, the web or flange portions 13 and 14 of the coupler and form pockets 18 and 19 therebetween for operatively engaging the curved edges of the flanges or webs 13 and 14, respectively, of the coupler. These pockets 18 and 19 are preferably formed with bearing surfaces coaxial with the pivotal member 6 for proper pivotal engagement with the portions 13 and 14 of the coupler.

The flanges 15 and 17 on the swivel block are provided with edge portions coaxial with the pivot pin, said portions cooperating, respectively, with correspondingly curved flanges 20 and 21 on the coupler. The central or intermediate flange 16 on the swivel block is intersected by a way or slot for the key 3 and is likewise formed with coaxially curved edges 22 and 23 for cooperation with the correspondingly curved pocket portions

24 and 25, respectively, on the main coupler portion. That portion of the swivel block rearwardly of the pivot pin 6 may be cored out, as indicated at 26, to decrease the weight thereof.

Although certain advantages of my invention may be secured by employing a pivot pin 6 circular in cross section, yet said pin is preferably formed flattened along the sides thereof providing a cross section with greater longitudinal than transverse dimensions. That is, the horizontal section of the pin, as shown most clearly in Figure 1, is formed substantially cylindrical, or circular in section, at its front and rear with straight sides connecting said circular portions. This construction is preferable in that a more efficient pin is thereby formed. Some of the advantages of a pin formed as disclosed are that with an oblong section a greater area of the pin with a given width between the loops of the yoke may be employed thereby strengthening not only the pivotal connection between the parts of the coupler but also the draft connection between the coupler and yoke. Likewise with a pin, the sides of which are flattened as shown, adequate shearing area or strength thereof may be secured with a pin of reduced width, as well as a wider marginal dimension for the coupler laterally of the pin, or increased transverse marginal dimensions of the overlapping or intercalated flanges of the coupler stem and/or swivel block, with the production of a more efficient construction of the parts of the articulated coupler. Another advantage resides in the provision of a more effective bearing area between the pin and the engaging flanges or webs on the main coupler portion and swivel block. It will be appreciated that a greater proportion of the forces are transmitted by the surface of the pin adjacent the front and rear thereof and that the surface thereof on the sides is of relatively little use for the purpose. Although the apertures through the engaging flanges on the main coupler portion and swivel block are formed to correspond with the size of the pin, yet, as illustrated most clearly in Figure 2, said apertures along the sides of both or of one of them, preferably the coupler, are desirably formed slightly angular with respect to the sides of the pin, as indicated at 27, to provide the desired clearance for permitting angling between the main coupler portion and the swivel block.

The pivot pin 6 is intersected or cut partly in half by a slot for the key 3. Although the engagement of said key in said slot in the pivot pin 6 tends to prevent removal of said pin when the key is in place, yet this construction is not primarily relied upon for the purpose. The slot in the pin is so large that considerable motion is permitted between it and the key thereby obviating break-

age of the pin to some extent. The normal means for preventing loss or undesired removal of the pivot pin comprise a shouldered portion 28 on the pin and a flange or shelf portion 29 on the swivel block 5 preferably positioned to the rear of said pin and extending forwardly into engagement with the same at the shouldered portion or notch 28 therein. The lower surface of the shelf portion 29 is preferably flush with the extreme lower end of the pin 6.

In order to allow for the reception of the shelf or web portion 29 extending from the swivel block 5 and the cooperating end of the pivot pin 6 and yet provide for the close fitting of the coupler butt in the front end of yoke, the lower web or arm 8 of said yoke is downwardly offset, as indicated at 30, from the normal elevation of the portion 8 to provide for receiving the lower end of the pin 6 and the retaining portion 29 of the swivel block. The side edges of the portion 30, however, preferably slope upwardly to the normal level of the arm 8 of the yoke to thereby closely engage the side portions of the swivel block. Not only are the coupler butt and swivel block closely engaged at top and bottom by the associated yoke but the sides thereof are also closely embraced between the walls or webs 9 and 10 of said yoke, sufficient clearance only being provided for allowing the desired angling between the members.

Referring particularly to Figure 4, an alternative retaining or securing means for a pivot pin 6^a preferably formed generally as heretofore described, is disclosed. In said modification, the lower web or flange 17^a of the swivel block 5^a is preferably formed with depending lug portions 31 provided with registering apertures 32 therethrough and the lower end of the pivot pin 6^a depending below the flange 17^a is likewise formed with a corresponding aperture therethrough. The pin 6^a, after insertion in place, is then retained in position and prevented from undesired loss or removal, either upwardly or downwardly, as well as turning thereof, by means of a cotter or similar locking means 33. Except as specifically described, the rest of the construction may be identical with that disclosed in connection with Figures 1 to 3, inclusive.

Referring specifically to Figure 5, a further modification of the pivot pin retaining means is illustrated. In said modification, the pivot pin 6^b is formed with a shouldered portion 34 and a tongue 35 split away from said shouldered portion. The foregoing retaining means may be formed by cutting or milling away a segment of the lower portion of the pin to form the shouldered portion 34. The swivel block and coupler butt, as heretofore with the exception of the lower flange or web 17^b of the swivel block, are formed with

registering apertures of suitable size for receiving said pin. The lower flange 17^b is preferably formed with a partially round and partially squared opening 36 so that, when the pivot pin is inserted in place after assembly of the coupler and swivel block, but before assembly with the yoke and key, the shoulder 34, upon insertion of the pin 6^b in place, will engage the straight or squared edge 37 of the aperture 36 and hold the pin in assembled relation or prevent further downward movement thereof. After said pin is in position, the tongue, which initially may extend axially with respect to the pin, having been formed by a saw cut 38 or in any other desired manner, preferably parallel with the base of the segmental portion cut out to form the shoulder 34, may be bent to the diagonal position illustrated where it will engage the adjacent portion of the flange 17^b of the swivel block and prevent undesired removal or motion of the pivot pin. After assembly of the coupler and swivel block by insertion and locking in place of the pivot pin 6^b, the members may be inserted between the arms of the yoke, as in the modification illustrated in Figures 1 to 3, inclusive, except that the lower arm 8 of said yoke need not be offset downwardly, as illustrated at 30, because in Figure 5 the lower end of the pin 6^b need not extend below the lower surface of the cooperating flange 17^b. Except as specifically described, the construction may be identical with that disclosed in connection with Figures 1 to 3, inclusive.

Referring to the drawings in general, it will be apparent that when the members are assembled, the forwardly extending arms 7 and 8 of the yoke will embrace the pivot pin therebetween and the swivel portion of the coupler, generally, the forwardly extending portions of the webs 9 and 10 serving to limit swiveling motion between the coupler and yoke. Although the forwardly extending arms 7 and 8 of the yoke would normally tend to prevent undesired removal or loss of the pin as well as the arrangement of said pin with respect to the key 3, yet the several retaining means illustrated not only prevent loss or undesired removal of the pin after assembly but allow substantially no motion between said pin and associated members and make it possible to assemble the coupler and swivel block without relying upon the cooperation of the key or yoke and without increasing, or only increasing to a slight degree, the overall height of the coupler butt and swivel block. Although in the present embodiment, the retaining means for the upright pivot pin or key are provided at the lower end of said pin to the rear or inner side thereof or extend through said pin between the rear and front thereof, yet I wish to be restricted only in accordance with the appended claims. It is not preferred to form

retaining means such as shown in Figure 5, on the front or outer side of the pivot pin, because the greatest stress between the swivel block and pivot pin occurs along the outer or front surface of said pin, so that it is not advisable to decrease the bearing area at such a place.

Having now described my invention, what I claim is:

10. 1. In a draft rigging, in combination with a yoke, a coupler, said coupler being formed with a stem composed of a plurality of parts pivotally connected by means of an upright pin intersecting said parts, the top of said pin being substantially flush with the top of the coupler stem and the bottom of said pin extending below the bottom of said coupler stem and supported by a flange extending from said stem, the upper and lower co-operating portions of the yoke extending forwardly beyond said pin and closely embracing the coupler stem, the lower portion of the yoke being downwardly offset adjacent said pin for receiving the lower end thereof.
15. 2. A yoke comprising forwardly extending arms connected at the forward ends by a hooded portion slotted for the reception of a draft key, one of said arms adjacent the forward end thereof being offset from and kept parallel to the longitudinal center line for receiving an extension from a co-operating coupler.
20. 3. In railway draft rigging, in combination with a yoke having top and bottom portions, a coupler stem comprising relatively movable parts, means for connecting said yoke and stem, and pivot means for connecting the parts of the stem extending below the lower face of said stem, said stem being closely embraced at top and bottom by the co-operating portions of the yoke, said portions extending above and below the pivot means and the lower portion formed to provide clearance for the lower end of said pivot means.
25. 4. In railway draft rigging, in combination with a vertical hooded yoke, a coupler stem extending into the hooded portion of said yoke, said stem comprising relatively movable parts respectively formed with normally horizontal apertured flanges arranged in overlapping relation, a normally upright pin passing through the apertures in said flanges for pivotally connecting said parts of the coupler stem, said pin terminating within the yoke and being provided with front and rear faces curved cylindrically about a common axis and laterally spaced flattened faces extending parallel to said axis, said apertures being correspondingly formed and providing clearance for permitting limited angling between said parts of the stem, whereby the apertured flanges are given wider marginal dimensions and the strength of the coupler

increased, and key means extending transversely of said pin for connecting said coupler to the yoke.

5. In railway draft rigging, in combination with a vertical yoke, a two-part coupler longitudinally movable with respect to said yoke, one of the parts of said coupler comprising a stem and the other a swivel block, an upright pivot pin extending through apertures in said stem and swivel block for connecting said parts, said pin and apertures being decreased in dimensions transversely of said coupler, as compared with their dimensions longitudinally of the coupler, whereby the marginal dimension of the coupler laterally of the pin is increased to improve the strength of the coupler for the transmission of service forces, and means for connecting said coupler and yoke.

6. A coupler comprising a stem and an associated swivel block, said stem and swivel block being formed with intercalated flanges, said flanges being apertured, and a normally upright pin passing therethrough, said stem, swivel block and pin being formed with a slot for receiving a horizontal draft key, said pin being generally cylindrical on its front and rear surfaces with its sides flattened to a width less than its longitudinal dimension, the apertures in said flanges being correspondingly formed and providing clearance for permitting limited angling between the stem and swivel block, whereby the flanges are given increased transverse marginal dimensions and the key-engaging wall of said slot is given a wider marginal dimension to increase the strength of the coupler for the transmission of service forces.

7. In railway draft rigging, in combination with a yoke having top and bottom portions, a coupler stem comprising relatively movable parts, means for connecting said yoke and stem, pivot means for connecting the parts of the stem extending below the lower face of said stem, and means extending from one of the parts of said stem below the lower face thereof for holding said pivot means in place, said stem being closely embraced at top and bottom by the co-operating portions of the yoke, said portions extending above and below the pivot means and the lower portion formed to provide clearance for the lower end of said pivot means and said holding means.

8. In railway draft rigging, in combination with a yoke having top and bottom portions, a coupler stem comprising relatively movable parts, means for connecting said yoke and stem, pivot means for connecting the parts of the stem extending below the lower face of said stem, and means extending through the lower end of said pin and coupler longitudinally of the coupler for holding said pin in place, said stem being closely embraced at top and bottom by the coop-

erating portions of the yoke, said portions extending above and below the pivot means and the lower portion formed to provide clearance for the lower end of said pivot means and said holding means.

5 In testimony whereof I affix my signature.
DONALD S. BARROWS.
